UNITED STATES PATENT OFFICE

2,684,144

COIN CONTROLLED LOCK MECHANISM

Henry L. Beimel, Cambridge, Mass., assignor to
 American Locker Company, Inc., Boston, Mass.,
 a corporation of Delaware

Application November 8, 1950, Serial No. 194,710

2 Claims. (Cl. 194—92)

1

This invention relates to coin controlled locks including a locking bolt movable to and from locking and releasing positions and means retaining the bolt in one of these two positions until rendered inoperative by the deposit of a coin of predetermined size in the lock. Coins of smaller size deposited into prior locks of the nature herein disclosed passed through the lock and into the cash box. Losses thus inadvertently sustained by customers have caused considerable dissatisfaction and ill will. The primary object of the invention herein resides in the provision of means for automatically returning such smaller coins to the customers and thereby eliminating this objection.

My improved lock is constructed to intercept only the coins of predetermined size, a return chute being provided for returning the smaller coins to the customers. The lock furthermore embodies means cooperating with the locking bolt for deflecting the intercepted coins into a coin receiving chamber when the bolt is moved from its normally retained position to the other position and the coin released. The production of an improved lock embodying these novel features comprises a further object of the invention.

These and other features of the invention will be best understood and appreciated from the following description of preferred embodiments thereof selected for purposes of illustration and shown in the accompanying drawings in which:

Fig. 1 is a front elevation of a lock embodying my invention, broken away to show the bolt in locking position,

Fig. 2 is a side elevation thereof partially broken away,

Fig. 3 is a fragmentary front view of the lock mechanism showing the parts in normal unlocked position,

Fig. 4 is a similar view showing the position of the parts when the lock has been turned to locking position and the intercepted coin released,

Fig. 5 is a side elevation, partially broken away, showing the deflecting of the intercepted coin into the coin receiving chamber,

Fig. 6 is a sectional view taken on line 6—6 of Fig. 2, and

Fig. 7 is a fragmentary rear elevation of Fig. 5.

The invention is particularly applicable to coin controlled locks of the nature shown in Patent 1,640,605 and, for purposes of description, I have herein disclosed my improved lock mechanism as applied to a parcel checking cabinet and requiring the insertion of a twenty-five cent coin to

2

release the lock which is normally held in the unlocked position of Fig. 3.

In the drawings, 9 indicates generally a key cylinder equipped with the usual locking tumblers adapted to be manipulated by a key 11, which in the type of lock illustrated serves as an identifying check by which the customer may recover or obtain access to the belongings which he has deposited in a parcel locker.

10 The key cylinder is provided near its outer end with a locking bolt 12, adapted to be moved with the cylinder from the unlocked position shown in Fig. 3 to the locked position shown in Fig. 1. A fragment of the front plate of the locker 15 cabinet frame is shown in Fig. 1 and indicated by reference character 13. The front plate 14 of the lock proper is disposed over an opening in the plate 13, its lower end being provided with a lip 15 engaging the inner face of the plate 13 and its upper end being equipped with a lock 16 by 20 which the plate 14 and the parts assembled thereon are detachably located in position in the cabinet. A recorder 17 may be connected to the lock so as to be operated by each actuation of the lock, 25 and whereby the number of lock actuations, and consequently the number of coins deposited, is recorded.

The front plate 14 is provided beneath the key cylinder with a coin slot 18, through which coins can be inserted edgewise into the coin receiving channel 19 rearwardly of the plate. The lock illustrated is adapted to operate on twenty-five cent coins 21 but not on coins 23 of smaller size. When a twenty-five cent coin is inserted it is held in the channel on and between a shoulder 20 and the laterally disposed end 22 of an arm 24 pivoted at 25 and, as thus supported, the coin is in position to be engaged by a feeler 26. The feeler is at the bottom end of a lever also pivoted at 25 and having an arm 28 provided with a tooth 30 for engaging in a notch 32 of the lock cylinder. A spring 33 normally swings the lever in a direction engaging the tooth in the notch which thereupon serves to hold the lock in the unlocked position of Fig. 3.

45 The arm 24 is held in the coin retaining position by a spring 34 anchored at its bottom end and having its top end engaged with a laterally projecting portion 35 of the arm. A tooth 36 carried by the arm extends into a recess 38 in the lock cylinder. A coin held in the position shown in Figs. 3 and 5 prevents entrance of the feeler into the coin channel, thereby preventing the tooth 30 from entering the notch 32, with the 55 result that the key cylinder is free to turn to

the locking position of Fig. 4. During this movement the cam shoulder 40 of the recess 38 engages the tooth 36 and swings the arms 24 outwardly, thus releasing the coin.

Disposed beneath the coin channel or slot is a coin return chute 42 open at the front 43, and rearwardly and laterally of the chute 42 is a coin receiving chamber 44, the wall 45 of the chute providing a partition between the chute and chamber. The lock illustrated is normally in the unlocked position of Figs. 2 and 3 and when coins 23 smaller than twenty-five cent coins are inserted through the coin slot 18 they drop straight down into the return chute 42, as illustrated in Fig. 2. The following described mechanism is provided for deflecting the twenty-five cent coins into the coin receiving chamber 44 when they are released from the end 22 of the arm 24.

Pivoted at 49 to a plate 46, supported on the lock frame 47 at 58, is a member 50 having a laterally extending free end 52 in the plane of the coin slot. A link 54 connects the member 50 with a plate 56 keyed to rotate with the lock cylinder. When the lock is in the unlocked position (Fig. 2) the end 52 of the member 50 is disposed to one side of the coin slot. When the lock is in the locked position (Fig. 5) the end 52 is disposed beneath the coin slot in position to intercept the coin and deflect it rearwardly into the coin receiving chamber 44.

It will now be apparent that coins smaller than twenty-five cent coins inserted into the lock will drop straight through the coin slot and be returned to the patron as illustrated in Fig. 2. A twenty-five cent coin inserted into the coin slot will be intercepted by and supported on the shoulder 29 and end 22 of the arm 24. When the lock is turned to the locked position (Fig. 5) the member 52 is brought to a position beneath the coin and the end 22 is withdrawn to release the coin. The coin thereupon drops onto the member 52

and is deflected into the coin chamber as illustrated in Fig. 5. A protective housing 58 mounted on the lock frame surrounds and protects the coin deflecting mechanism.

Having thus disclosed my invention what I claim as new and desire to secure by Letters Patent is:

1. A coin controlled lock, comprising a locking bolt mounted for movement to and from locking and released positions, means including a latch normally retaining the bolt in one of said positions, means providing a coin receiving channel in the lock, means providing a coin return chute directly beneath the channel and a coin receiving chamber laterally thereof, means operatively associated with the bolt and disposed in the channel above the coin return chute for intercepting and holding a coin of predetermined size but ineffective to intercept a coin of smaller size and prevent its passage downwardly into the return chute when the bolt is in said one position, means including a feeler operative on a coin thus intercepted for rendering said latch inoperative, means operatively associated with the bolt for releasing the intercepted coin when the bolt is moved from said one position to the other position, and means movable to coin deflecting position by movement of the bolt to said other position to intercept the released coin and deflect it into said laterally disposed chamber.

2. The coin controlled lock defined in claim 1 in which return movement of the bolt moves the last named means away from said coin deflecting position.
